UNITED STATES PATENT OFFICE.

HENRY C. SERGEANT, OF NEW YORK, N. Y., ASSIGNOR TO THE INGERSOLL
ROCK DRILL COMPANY, OF SAME PLACE.

REGULATOR FOR COMPRESSORS.

SPECIFICATION forming part of Letters Patent No. 415,370, dated November 19, 1889.

Application filed January 6, 1888. Serial No. 259,956. (No model.)

To all whom it may concern:

Be it known that I, HENRY C. SERGEANT, of the city and county of New York, in the State of New York, have invented a new and useful Improvement in Regulators for Air-Compressors, of which the following is a specification.

In the operation of air-compressors the air is usually pumped by the compressor-cylinder and piston into a receiver or tank, from which the supply is taken for operating various machines. This tank is provided with a safety-valve, and a regulator is now commonly employed, which is operated by the pressure of air in the receiver or tank, and which, when the pressure exceeds the normal pressure or that desired, serves to close the throttle-valve of the operating-engine or cause the inlet or suction valves of the compressor-cylinder to remain open during the continued operation of the piston, or to perform both these operations.

The object of my invention is to provide a regulator which, when the air in the receiver or tank exceeds the pressure desired, will operate to cause the outlet or discharge valves of the compressor-cylinder to remain open, and thereby admit the full pressure of the receiver or tank on both sides of the compressing-piston, and which will also preferably cause the throttle-valve of the operating-engine to be closed or partially closed; and a further object of my invention is to provide a regulator which in case of the receiver or tank or the air-pipe leading thereto bursting will cause the discharge-valves of the compressor to remain open, and will also produce the closing of the throttle-valve of the operating-engine.

The invention will be hereinafter particularly described, and pointed out in the claims.

In the accompanying drawings, Figure 1 is a sectional elevation showing portions of a compressor-cylinder, the throttle-valve for its operating-engine, and regulator mechanism embodying my invention. Fig. 2 is a transverse section upon the plane of the dotted line $x-x$, Fig. 1, looking toward the left from said line. Fig. 3 is a transverse section upon the plane of the dotted line $y-y$, looking to-

ward the left from said line; and Fig. 4 is a sectional elevation, similar to Fig. 1, of the regulator-valve and motor, showing the valve in the position which it occupies when its motor has been operated by the excess of air- 55 pressure in the receiver or tank.

Similar letters of reference designate corresponding parts in all the figures.

A designates the compressor-cylinder, in which operates the piston B, and which is closed at the ends by heads A'. These heads are constructed to form discharge-chests C, which communicate with a passage C', extending lengthwise of the cylinder; and c designates the discharge-opening, with which is connected the air-discharge pipe leading to the receiver or tank. (Not here shown.)

The suction or inlet valves of the compressor-cylinder A may be of any suitable construction, as my invention in no wise relates to them, and they are not here shown.

The discharge-valves D, which close against puppet-like seats a in the cylinder-heads, have combined with them pistons, and in the present example of my invention the valves are represented as cylindric shells of cup-shape form and constitute puppet-valves and pistons. The cylindric piston portions of these valves fit within cylinders a', formed in the heads A' and in line with the valve-seats, and these cylinders are closed at their outer ends by heads a''. (Here represented as in the form of plugs screwed into such cylinders.) The valves D are closed by springs d, applied within them in a well-known manner, and the rear ends of the piston portions of the valves, when the valves are open, should close against these plugs, so as to form air-tight joints, and so that, even though there may be a slight leakage between the pistons and the cylinders a', such leakage cannot enter the back of the valves when the valves are open.

E designates the shell of the throttle-valve, which is to be applied to the operating-engine, and E' designates the valve of the throttle, which is nearly balanced, but has a slight preponderance of pressure, tending to close it.

To the stem e of the valve is fixed a piston e', and a sufficient pressure within the cylinder e'', back of the piston, will hold the valve 100

open, while a reduction or entire relief of such pressure will permit the valve to close by the unbalanced pressure of steam upon it. The cylinder e^2 may be formed in a bridge-piece e^3 , supported by posts e^4 from the shell of the valve, and upon the valve-stem are fitted adjustable nuts e^5 , which, in the closing movement of the valve, are arrested by the bridge-piece e^3 and form an adjustable stop 10 for limiting the closing movement of the valve. These nuts e^5 may be so set that when pressure in the cylinder e^2 is relieved sufficiently to permit the valve E' to be closed or partially closed the nuts e^5 will arrest the 15 closing movement of the valve and hold it slightly open, so as to admit sufficient steam to turn over slowly the operating-engine.

In first starting the compressor there will be no pressure whatever in the cylinder e^2 , 20 and before the stop-valve of the operating-engine is opened the throttle-valve E' may be opened by hand, and a hook e^6 , pivoted to the bridge-piece e^3 , may be swung into engagement with the shoulder e^7 upon the valve- 25 stem, as shown in Figs. 1 and 3, so as to hold the throttle-valve open, and the stop-valve may then be opened and the machinery started. After the pressure of air has accumulated so that the cylinder e^2 is filled, as 30 hereinafter described, with air under a sufficient pressure to hold the throttle-valve open, the hook-shaped stop e^6 may be swung out of the way, as shown by dotted lines in Fig. 3, and the throttle-valve E' thereafter held open 35 by the pressure in the cylinder e^2 .

With the back of each of the cylinders a' e^2 communicate pipes ff' , which lead from a regulator, whereby the pressure of air within the receiver or tank (not shown) is admitted 40 to these cylinders so long as the air-pressure does not exceed that desired, and whereby the compressed air is cut off from these cylinders and these cylinders relieved of pressure when the compressed air in the receiver 45 or tank exceeds that desired. This regulator is best shown in Fig. 4, but also in Figs. 1 and 2. It comprises a valve whereby the aforesaid results are accomplished and a regulator-piston fitting a regulator-cylinder which is 50 in communication with the receiver or tank.

F designates the valve-box of the regulator, with which the pipes f communicate, and with which the pipe f' communicates by a cored passage f^2 . As here represented, this valve-box communicates by an opening f^3 with the atmosphere, and G designates the regulating-valve, which is represented as of cylindric form and as having fixed upon it or formed with it the regulator-piston H . H' designates 55 the regulator-cylinder, to which said piston is fitted, and the said regulator-piston H is loaded by weights or equivalent devices applied in any suitable manner. As here represented, this loading of the piston H is accomplished by a lever H^2 , pivoted at h , and from which are hung weights h' , and it will be understood that any number of weights

are to be applied, according to the pressure which it is desired to maintain within the tank or receiver. The valve G is of cylindric form, and is provided with passages g g' g^2 , whereby the valve-box F may be placed in communication with the pipe I , leading from the receiver or tank, or cut off from such communication, according as said valve G is 70 moved by the regulator-piston H . I have also shown the regulator-cylinder H' as formed with the passage h^2 , whereby air is admitted from the pipe I to the regulator-cylinder to act upon the regulator-piston. 75

The regulating devices H H' F G may be 80 may be supported by a bracket or arm H^3 from the cylinder A , as best represented in Fig. 2, or in any other suitable manner. It will also be seen that the lower end of the 85 valve G normally closes the opening f^3 , through which the valve-box F communicates with the atmosphere.

Referring now to the operation of my devices, it will be understood that Fig. 1 shows 90 the position of parts during the normal operation of the compressor and so long as the pressure within the tank or receiver does not reach the limit for which the regulator-piston H is loaded. The pipe I , leading from the 95 receiver or tank, is in free communication through the ports g g' g^2 with the valve-box F , and from the valve-box the compressed air of like pressure passes through the pipes ff' to the cylinders a' e^2 . This pressure being 100 upon the backs of the valves D , they open and close normally, or, in other words, they close by the preponderating force of the springs d , and the pressure admitted to the cylinder e^2 of the throttle-valve holds said throttle-valve 105 fully open. If now the pressure in the receiver or tank rises above the limit desired, the regulator-piston H is forced upward, thereby cutting off communication of the pipe I with the valve-box F and throwing open the 110 valve-box F through the rising of the valve G and the opening of the aperture f^3 to the atmosphere. The pressure within the cylinders a' e^2 is thus at once relieved, the throttle E' is automatically closed or nearly closed, 115 thereby stopping or slowing up the operating-engine, and as soon as the discharge-valves D are forced from their seats a by the pressure of air in the compressor-cylinder they remain open because the pressure behind them 120 in the cylinders a' is relieved, and the full tank-pressure is thus admitted on both sides of the main operating-piston B . It is important that the back ends of the valves D , or rather of their balancing-pistons, should close 125 tightly against the heads of the cylinders a' , so that any leakage which may pass through the discharge-chests C between said pistons and the walls of the cylinders a' cannot have access to the backs of the discharge-valves 130 D . As soon as the pressure in the receiver or tank falls below the limit the regulator-piston H falls, thereby moving downward the valve G and again closing the opening f^3 and

placing the pipe I in communication with the valve-box F, as before. The cylinders $a' e^2$ again receive the pressure of compressed air, the throttle-valve E' is opened, the discharge-valves D closed, and work proceeds as before.

Another accident which sometimes happens with air-compressing machinery is the bursting of the receiver or tank, thereby relieving the operating-engine of the principal part of its work. If such accident should occur, it will be obvious that the valve-box F, being in communication with the pipe I, will be relieved of pressure, and through the pipes $f f'$ the pressure in the cylinders $a' e^2$ will be relieved and the throttle-valve of the engine will be closed by the pressure of steam upon it, thus preventing the engine from running away.

From the above description it will be apparent that the piston e' and cylinder e^2 may be properly termed a "motor for holding the throttle-valve open," and the cylinder H' and piston H may be properly termed a "motor for operating the regulator-valve G."

It will be understood that the air-pipe I in all cases leads from the air which is to have its pressure governed or regulated, and the result is the same whether the pipe I leads directly from the receiver or tank or from the pipe which delivers air from the compressor-cylinder to such receiver or tank.

What I claim as my invention, and desire to secure by Letters Patent, is—

1. The combination, with the cylinder of an air-compressor, of a combined discharge-valve and piston therefor, a cylinder to which the said piston is fitted, an air-receiver, a valve-box connected by pipes with the said piston-cylinder and with the air-receiver or an appurtenance thereof, a regulating-valve in said valve-box provided with passages affording communication between said pipes, a motor connected to said valve and moving in one direction to raise the valve and to close said passages upon the occurrence of excessive pressure at the receiver and operating upon the decrease of such pressure to shift said regulating-valve to open said passages, substantially as and for purpose specified.

2. The combination, with an air-compressor and a throttle-valve through which its operating-engine is supplied with steam, of a motor-cylinder and piston for holding said throttle-valve open, a valve-box and pipes leading thereto from the motor-cylinder and from the air-receiver or an appurtenance thereof, a regulating-valve, whereby communication between said pipes is normally maintained, and whereby the said valve-box is relieved of pressure when the valve is moved to break such communication, and a motor operated upon by pressure from the air-receiver for operating the regulating-valve, substantially as herein described. 55

3. The combination, with the throttle-valve E' and its stem, of the motor for holding the valve open, consisting of a cylinder e^2 and a piston e' , fitting the cylinder and secured to the valve-stem, and the nuts e^5 , threaded upon the valve-stem and forming an adjustable stop for limiting the closing movement of the valve, substantially as herein described. 60

4. The combination, with the throttle-valve E' and its shouldered stem e , of the motor for holding the valve open and a pipe for supplying compressed air to operate the motor, and a stop, as hook e^6 , movable to engage it with or disengage it from the shoulder of the valve-stem, substantially as herein described. 75

5. The combination, with an air-compressor cylinder and its combined discharge-valves and pistons D, of the cylinders a' , the valve-box F, having an opening to the atmosphere, the inlet-pipe I, for compressed air, and the pipes f , connecting the valve-box and cylinders, the piston-valve G, whereby the said pipes f are normally maintained in communication, and which normally closes said opening to the atmosphere, and a motor acted upon by compressed air of the receiver or tank-pressure to cut off communication between the valve-box and the pipe I and to uncover the said opening to the atmosphere, 85 substantially as herein described. 90
